UNITED STATES PATENT OFFICE.

CHRISTIAN COOK, OF BALTIMORE, MARYLAND.

ASH-SIFTER.

SPECIFICATION forming part of Letters Patent No. 248,714, dated October 25, 1881.

Application filed June 14, 1881. (No model.)

To all whom it may concern :

Be it known that I, CHRISTIAN COOK, of the city of Baltimore and State of Maryland, have invented certain Improvements in Ash-Sifters, 5 of which the following is a specification; and I do hereby declare that in the same is contained a full, clear, and exact description thereof, reference being had to the accompanying drawings, and to letters of reference marked 10 thereon.

This invention relates to certain improvements in that class of ash-sifters in which a cylindrical sieve is revolved within a box by means of an exterior handle; and it consists in 15 the peculiar construction of the said box which admits of a close joint being formed between the lid and box proper, and also of the ready removal of the sieve when the same or the box has to be emptied of its contents.

20 In the further description of my said invention which follows reference is made to the accompanying drawings, forming a part hereof, and in which—

Figure I is a longitudinal section of the improved ash-sifter. Fig. II is an end view of the same with the lid removed. Fig. III is an isometrical view of a part of the lid.

Similar letters of reference indicate similar parts in all the views.

25 A is the revoluble sieve.

B is the inclosing box, having the lid thereof in two sections, *a* and *b*. One end of the spindle *c* of the sieve rests in a hole in the side

of the box, but the other end extends to the outside of the box, where it is provided with a 35 handle, *C*. To admit of the removal of the sieve and its spindle the side of the box next to the handle extends upwardly only to the center of the spindle; but the space above the spindle, when the sifter is in use, is closed by 40 section *b* of the lid. This section of the lid, which is shown detached in Fig. III of the drawings, has a tongue at either end, and also one at its lower edge, which tongues fit into 45 grooves in the box, and it is notched to fit over spindle *c*. When the section *b* is in place the box is ready to receive the remaining section, *a*, of the lid, which has tongues at its lateral edges and inner end which fit into correspondingly-shaped grooves in the box.

50 By this construction of the box and its lids no escape of ashes can take place as the sieve is revolved, while ample space is left when the lids are removed for the withdrawal of the sieve.

I claim as my invention—

55 In combination with the box *B* and the removable sieve and spindle, respectively represented by *A* and *c*, the sections *a* and *b* of the lid, the latter being notched to fit over the spindle *c*, all arranged substantially as specified. 60

CHRISTIAN COOK.
